PORTABLE RESISTANCE UNIT

Fry Hanna, Logan, W. Va., assignor to Guyan
Machinery Company, Logan, W. Va., a corpora-
tion of West Virginia

Application April 30, 1935, Serial No. 19,094

2 Claims. (Cl. 201—67)

This invention relates to electrical resistance units and particularly to the structural details of such a unit which make it rugged, durable, easily accessible for inspection and repair, and well 5 ventilated.

In the prior art it has been difficult to obtain a resistance unit which was sufficiently rugged and free from failures to make it suitable for use in rail bonding and mine repair work where available voltages usually exceed those to be used in welding or other repairing. Work of this character is very frequently carried on under severe atmospheric conditions where the air contains a large percentage of moisture, and hence the majority of the electrical failures have been due to 10 grounding of the resistance coils or of the connections to them. Consequently, the object of this invention is to provide a rugged resistance unit which will be durable and will have an unprecedented freedom from grounding failures.

Briefly stated, the invention consists in a resistance unit having a plurality of resistance coils carried between spaced insulating supports and supported at intermediate points by perforated sheets of moisture resisting pressed insulating 25 material which is entirely free from any metallic content. The unit so constructed is covered over by an apertured casing which permits free flow of air over and about the resistance coils and at the same time leaves all of the resistance coils open 30 for inspection and repair without requiring difficult dismantling operations.

Other objects and advantages of the invention will be apparent from the following specification when read in conjunction with the accompanying 35 drawing in which:—

Figure 1 is a side view of one form of electrical resistance unit embodying this invention, certain parts of the unit being shown in section.

Figure 2 is a partial section on line 2—2 of Figure 1; and

Figure 3 is a detail view of one of the resistance coils removed from the unit so as to illustrate the manner of mounting the coils.

The resistance unit shown in the drawing comprises a substantially flat metallic base 5 having upstanding lateral flanges 6 and reentrant end flanges 7 contacting with the ends of the unit. The base 5 is covered by a sheet of insulating material 8 extending throughout its length and contacting with the inner face of each of two spaced end members 12 projecting upwardly from the base and attached to it by means of angle members 9, bolts 11, and rivets 10.

Covering the outer face of each of the end

members 12 is an insulating plate 13 held in position by the reentrant end flanges 7 at the bottom, and adapted to cover up and protect the metallic supports for the resistance coils.

The end members 12 are connected at the top by a perforated sheet metal plate 14 secured to these end members by angle plates 15 and bolts 16. The lateral sides of the plate 14 are bent down over reticulated side shields 17 composed preferably of expanded metal. The top 14 is secured to the side shields by bolts 18 which serve the purpose, not only of holding the parts of the casing together, but supporting in spaced relation certain elements later to be described. The lower edges of the side shields 17 are secured to the lateral flanges 6 of base 5 by means of bolts 19. Angle plates 21 cover the exposed ends of the side shields 17 and these plates are secured to the end members by screws 23. Inasmuch as the unit is constructed for portable use, it may carry handles 20 secured to the top 14, these handles being of any suitable form.

It will be understood from the preceding description that the end members in conjunction with the base, the perforated top, and the reticulated side screens, form an enclosing casing which permits free flow of air therethrough. Mounted within this casing are a plurality of electrical resistance coils 24 composed preferably of non-oxidizing material and each having substantially the form indicated in Figure 3 of the drawing. Each of these coils 24 is connected to both of the end members 12, and each coil is provided for this purpose with a hook portion 25 terminating in an eye which may receive a bolt 26 for securing it either to the eye of an adjacent coil or to a terminal connection. The hook portions 25 are attached to hooks 27, each having a threaded shank 28 passing through openings in the end members 12 and secured by nuts 29. Each of these shanks preferably carries an enlarged collar to limit the entrance of the shank into the end members.

As shown in Figure 1, the resistance coils are arranged in vertical rows, each row containing five of the coils, four of these being paired and the remaining one having a free end attached to a hook 31 terminating in an eye and secured to the eye of the resistance coil by a bolt 32. An angle piece 33 is also secured by the bolt 32 and forms an electrical connection between the top coil 24, and a terminal bolt 34 passing through the end member 12 so as to clamp the end member 12, the facing plate 13, and the angle member 33

in fixed relation. This bolt also serves as a means of obtaining electrical connection to the resistance coil without the use of switches or plugs.

The resistance coils 24 are supported at intermediate points between the end members 12 by supports 36, each composed of insulating material such as compressed asbestos lumber perforated at 37 to permit the coils to pass through them. As shown in Figure 1, the unit has three of these supports 36, each resting upon the insulating lining 8 and held in spaced relation by deflected portions 38 of the lateral flanges 6, and between clips 39 and nuts 41 associated with bolts 18. The insulating supports 36 are consequently held in permanent fixed spaced relation by the deflected portions 38 at both sides of the bottom of the casing and by two of the clips 39 adjacent the top of the casing.

These supports being composed entirely of insulating material, prevent sagging of the resistance coils and there is no possibility of breakage, causing failure of the unit. Additional connections may be made to the resistance coils 24 by means of the terminals 35 carried by the right hand end member shown in Fig. 1. Inasmuch as these connections will be similar to those indicated in connection with the terminal 34, a detail description will not be necessary.

It will be apparent from the preceding description that this unit comprises a simple sturdy frame in which the resistance coils are mounted and in which all of the electrical connections are visible for inspection. Each of the resistance coils can be removed readily in case of breakage, since the various coils are not embedded. This complete exposure also facilitates flow of air in and about the coils so that they may operate efficiently and without overheating. The fact that no conductor passes through metal, renders grounding possible only by a long surface leak. While only three of the supports 36 are indicated, it will be obvious that more of these supports may be employed when the resistance coils 24 are made of light material, and in this way all possibility of two adjacent coils coming into contact can be avoided.

Although only one embodiment of the invention has been described, it will be obvious that various changes may be made in the details of the construction within the scope of the claims,

without departing from the spirit of the invention.

What I claim is:—

1. An electrical resistance unit comprising a flat metal supporting base adapted to rest directly on the surface of the ground and having upstanding lateral and end flanges, said end flanges forming surfaces inclined to the ground and adapted to ride over small obstructions; an upstanding end member of insulation at each end of said base engaging said end flanges; a perforated metal top sheet connecting said end members together; a plurality of insulating supports of compressed material, said supports having spaced openings therein; deflected tangs on said lateral flanges for holding said supports in fixed relation to said base; clamps on said top for holding said supports; a plurality of resistance coils slung between said end members and passing through and positioned by the openings in said supports; means on one of said end members for supporting said coils and insulating them against contact with objects outside of the unit; means on the other end member for making electrical connections to said coils, and side screens of expanded metal cooperating with said end members, said base and said top to form a ventilated enclosing casing.

2. An electrical resistance unit comprising a flat insulated metallic base having upstanding lateral flanges with spaced deflected portions thereon, and reentrant end flanges; upstanding end members of insulation secured on said base and engaging said reentrant end flanges, said base being adapted to rest directly upon the ground and said reentrant flanges permitting the base to slide over small obstructions; a plurality of perforated spaced supports made up entirely of insulation and held in spaced relation by engagement with the deflected portions of said base; coil supporting means on each of said end members; a plurality of resistance coils slung between the means on said end members and passing through the perforations in said spaced supports; a metal plate on one of said end members for enclosing the coil supporting means and insulated from it; terminal means on the other end member and connected to said coils; and a perforated cage-like cover secured to said end members and said spaced supports.

FRY HANNA.

CERTIFICATE OF CORRECTION.

Patent No. 2,076,561.

April 13, 1937.

FRY HANNA.

It is hereby certified that error appears in the printed specification of the above numbered patent requiring correction as follows: Page 2, second column, claim 2, lines 34 to 37, strike out the comma and phrase ", said base being adapted to rest directly upon the ground and said reentrant flanges permitting the base to slide over small obstructions" and insert the same after the word flanges and before the semi-colon in line 32, of said claim; and that the said Letters Patent should be read with this correction therein that the same may conform to the record of the case in the Patent Office.

Signed and sealed this 8th day of June, A. D. 1937.

Henry Van Arsdale
